ALBERT J. GATES, OF CHICAGO, ILLINOIS, ASSIGNOR TO ALLIS-CHALMERS COMPANY, OF CHICAGO, ILLINOIS, A CORPORATION OF NEW JERSEY.

FEED MEANS FOR TRACTION-ELEVATORS.

No. 867,495.

Specification of Letters Patent.

Patented Oct. 1, 1907.

Application filed February 13, 1905. Serial No. 245,545.

To all whom it may concern:

Be it known that I, ALBERT J. GATES, a citizen of the United States, residing at Chicago, in the county of Cook and State of Illinois, have invented certain new and useful Improvements in Feed Means for Traction-Elevators, of which the following is a specification.

This invention relates to means for introducing crushed ore, stone or other material into the buckets 10 of a rectilinearly traveling elevator, usually vertical, in such a manner that the spilling out of material, as ordinarily spouted into the elevator, is avoided. Its object is to prevent large pieces, commonly called spawls, from partially entering the bucket and afterward coming in contact with the end of the discharge 15 spout, thereby frequently causing great damage either by destruction of the elevator buckets, or breaking of the chain or other flexible means upon which the buckets are mounted.

20 The invention consists generally of an apron or baffle plate used in connection with the spout discharging the material to the elevator, this baffling plate being of a width slightly in excess of the width of the bucket and extending downward from the end 25 of the discharge spout a sufficient distance dependent upon the size of the elevator buckets so that there is always one bucket in its proper position with relation to the apron for receiving the material from the discharge spout, before the preceding bucket passes the 30 end of the spout. This apron therefore is fixed as referred to the framing 2. With such a structure all the material from the discharge spout must enter the elevator buckets, and, owing to the presence of the apron, it is impossible for any to overhang the edge of the 35 bucket, or catch on the under edge of the discharge spout as the bucket is being elevated.

For a more specific disclosure of my invention, reference is made to the accompanying drawing, in which,—

Figure 1 is a plan view of the discharge spout and 40 elevator, showing but one bucket. Fig. 2 is an elevation, partly in section, of the discharge spout, apron, and a portion of the elevator.

The feed spout 1 is located upon framing 2, so as to deliver by gravity to the elevator 3, material placed 45 upon it. This elevator is of the ordinary construction, consisting of a flexible means, such as a chain or other means, here shown as a belt 4, upon which in any convenient way are mounted buckets 5. This flexible means is not shown in Fig. 2. The buckets 5 are attached to the belt 4 in any convenient way; that 50 shown consists in fastening to the belt 4 transverse rods 6, to which the buckets 5 are attached. Upon the ends of the rods are mounted rollers 7. These rollers co-act with wheels 8 at the top and bottom of 55 the elevator. The wheels 8 are adjustable so as to

tighten the belt by means of the screw 9. They may be grooved as shown for use with chains if desirable so that the belt 4 may be dispensed with. As this forms no part of my invention, I will not describe it in detail. The spout 1 is unobstructed as to the passage of material over it by gravity and may be termed an unobstructed gravity spout.

At the delivery end of the feed spout 1, is located an apron 10. This apron depends from the end of the feed spout in a direction along the edges of the ascending buckets 5, so as to co-act therewith. The apron has upwardly extending arms 19, within which the sides of the spout 1 extend. The apron 10 extends down a sufficient distance so as to be in tangential relation to the path of the receiving edges of the ascending buckets; that is, the apron extends down a little beyond the upwardly rectilinearly traveling portion of the elevator. Or, the tangential relation may be established by placing the apron along the rectilinearly traveling portion of the elevator and curving the lower 70 end of the apron away from that portion of the elevator. The former arrangement is preferable as the maximum effect of the elevator can be utilized as the spout is relatively lower respecting the elevator.

In either arrangement, the essential feature is that 80 the plane portion of the apron should be of an extent below the plane of the spout at least equal to the distance between the receiving edges of two consecutive buckets traveling rectilinearly. That is, this extent should be at least equal to the pitch of the buckets. 85 This essential feature will insure at least one bucket being in co-action with the apron at all times and so prevent material from projecting beyond the receiving edges of the buckets. If necessary, guides may be provided for the rollers 7 for the rectilinear travel of 90 the elevator so as to insure co-action of the receiving edges of the buckets 5 with the apron 10, but the elevator tightening means 9 will ordinarily be sufficient, to insure such co-action. The delivery end of the 95 spout 1 is narrower than the buckets 5, and the latter narrower than the apron 10, to prevent spilling of material.

In accordance with the provisions of the patent statutes, I have described the principle of operation of my invention, together with the apparatus which I now consider to represent the best embodiment thereof; but I desire it to be understood that the apparatus shown is merely illustrative and that the invention can be carried out by other means.

I claim as my invention:—

1. In a feed means for traction elevators, the combination of a rectilinearly traveling elevating means, an unobstructed gravity spout feeding to said elevating means, and a fixed apron depending from the spout and co-acting therewith and with the elevating means.

2. In a feed means for traction elevators, the combination

105

110

tion of a sectional rectilinearly traveling elevating means, a discharge spout feeding to said elevating means, and an apron having its portion within the limits of width of the discharge, below the discharge.

5 3. Traveling buckets, an unobstructed spout feeding to the buckets, and a fixed apron depending from the spout.

4. Traveling buckets, a discharge spout feeding to the buckets, and an apron having its portion within the limits of width of the discharge, below the discharge.

10 5. Traveling buckets, an unobstructed spout feeding to the buckets, and a fixed apron depending from the spout and of length sufficient to constantly co-act with at least one of the buckets.

6. Traveling buckets, a spout in feeding relation to the buckets, and an apron depending from the spout, the

buckets being at least as wide as the spout discharge and the apron being at least as wide as the buckets.

7. In a feed means for traction elevators, a flexible means, buckets thereon, a gravity spout in feeding relation to the buckets, and an apron depending from the spout, the buckets being at least as wide as the delivery end of the spout, and the apron being at least as wide as the buckets. 20

In testimony whereof I affix my signature in presence of two witnesses.

ALBERT J. GATES.
